UNITED STATES PATENT OFFICE.

MILO COVEL, OF CHICAGO, ILLINOIS.

DEVICE FOR HOLDING AND DRESSING SAWS.

SPECIFICATION forming part of Letters Patent No. 398,031, dated February 19, 1889.

Application filed October 18, 1888. Serial No. 288,455. (No model.)

To all whom it may concern:

Be it known that I, MILO COVEL, of Chicago, county of Cook, and State of Illinois, have invented certain new and useful Improvements in a Device for Holding and Dressing Saws, of which the following is a full, clear, and exact description, that will enable others to make and use the same, reference being had to the accompanying drawings, forming a part of this specification.

The object of this invention is to provide a convenient device for clamping and holding saws during the operation of dressing the teeth, the improvement being more especially intended for use in connection with straight and band saws, as will be hereinafter set forth.

Figure 1 is a side elevation of a device embodying my improved features; Fig. 2, a plan or top view of a hand-gage used in connection with the clamping and holding mechanism. Fig. 3 is a vertical transverse section of the cap-plates, the clamping-bars, and the gage illustrated in Fig. 2, the saw being shown in position to be operated upon. Fig. 4 is a similar view as that illustrated in Fig. 3, with this difference: a hand-setting tool being substituted for the hand-gage. Fig. 5 is a vertical transverse section in plane 5, Fig. 1, looking in the direction indicated by the arrow; Fig. 6, a broken-away side elevation of one of the frames, showing the opposite side from that illustrated in Fig. 1. Fig. 7 is a broken-away detail of the upper end of one of the adjustable rack-bars which support the saw; Fig. 8, a broken-away horizontal section in plane 8, Fig. 1; Fig. 9, a broken-away horizontal section in plane 9, Fig. 1. Fig. 10 is a plan or top view of a hand-tool for holding a flat file for top-dressing the points of the teeth; Fig. 11, a similar view of a hand-tool arranged to hold an angular file and used in side-dressing the teeth. Fig. 12 is a transverse section of the hand-tool illustrated in Fig. 10, showing the upper part of the saw-holding device and the relative position of these parts; and Fig. 13, a similar view, the hand-tool for side-dressing the teeth being shown in position for use.

Referring to the drawings, A A' represent the ends forming the supporting-frame. These end castings will be a little over three feet in

height, while the longitudinal dimensions of the machine will be about five feet.

A² A³ are horizontal angular cap-plates. The cap-plate A² is rigidly secured to the highest side of the framing ends by means of the bolts a, as shewn in Figs. 1 and 5. The opposite side of the frame is cut away, as at a', so that the companion or movable cap-plate A³ can pass just over the same when moving toward or away from the stationary plate A². The respective ends of cap-plate A³ are rigidly bolted to the upper ends of the vertical levers B B', which are located at each end and just inside of the frame, as shown in Figs. 1, 5, and 6. The lower ends of these levers are pivoted on the bolts a².

The bars B² B³, for clamping and holding the saw during the operation of dressing the same, are properly secured to the upper sides of the cap-plates. The cap-plates are provided on the upper side with the shallow recess a³, in which the clamping-bars B² B³ fit, and thereby prevent a lateral pressure from straining them out of a true position. The inner adjacent edges of the clamping-bars project a little over the vertical faces of the cap-plates, (see Fig. 5,) so as to clamp the saw on a line with the base of the teeth and hold the same firmly in a rigid position.

The bolts a⁴ pass up through the respective ends of the cap-plates A² A³ and bear against the under side and ends of the saw-clamping bars for the purpose of springing the ends of said bars upward a little when it is desired to dress a straight saw, so as to impart a slight concavity to the cutting-edge—that is, a gradual hollowing from both ends of the saw in the direction of the center. Ordinarily, however, and especially when dressing band-saws, the clamping-bars will lie flat on their bed. The clamping-bars being secured to the cap-plates forming the bed by means of a number of screws, a⁵, it is therefore necessary to slack up a little on the screws nearest the ends of the bars when springing the same upward by means of the bolts a⁴.

The reduced end of the horizontal shaft B⁴ is provided with suitable journal-bearings in the frame, (see Fig. 1,) while the larger or cam part a⁶ is journaled in the levers B B', as shown in Fig. 5. Turning the lever-han-

dle a^1 , mounted on the shaft B^4 , downward has the effect of moving the adjustable cap-plate A^3 , carrying the clamping-bar B^3 toward the companion parts and tightly securing the saw a^8 in position to be operated upon. The upward or opposite movement of the handle a^1 spreads the clamping-jaws and releases the saw.

At each end of the machine and just inside 10 of the frame are located the vertically-adjustable rack-bars $C C'$, provided in the upper end with the V-shaped notch b , in which rests the back edge of the saw while being dressed. The upper ends of the rack-bars are also provided 15 with the guide-lugs b' , (see Fig. 7,) correspondingly notched, which engage with the opening b^2 in the upper part of the framing ends, as shown in Fig. 5, and assist in keeping the rack-bars in their proper position. 20 The dotted lines in Fig. 5 indicate the bottom of the opening and the position of the lugs b' .

C^2 is a rock-shaft journaled in the framing parts near their longitudinal center, and has 25 the pinions b^3 mounted on the respective ends thereof, and which engage with the lower toothed ends, b^4 , of the rack-bars. By means of the handle b^5 the rock-shaft may be rotated in either direction in raising or lowering the 30 rack-bars when bringing the saw into proper position. The springs b^6 are coiled on the rock-shaft adjacent to each end, one end of the springs being secured to the bolts b^7 , set in the shaft, and the opposite ends secured to 35 the pivot-bolts a^2 . These springs are set so that the pressure of the same will be in an upward direction with reference to the rack-bars and automatically returns the same to their highest or normal position. 40 b^8 is the lower guide-brackets (see Figs. 5 and 8) for the rack-bars $C C'$, and b^9 the upper guide-brackets, both of which are bolted to the inside of the frame-work. The upper brackets also support the respective ends of 45 the tool-table C^3 . The rack-bars are secured in a stationary or fixed position by the hand-screws C^4 .

The rectangular hand-gage D (see Figs. 2 and 3) is provided in each corner with the adjustable screw-bolts d , which project from the under side of the gage-plate. In practice these screw or gage bolts will be set in accordance with the distance it is desired to have the teeth of the saw project above the clamping-bars. The saw is first placed loosely in position, the back edge resting in the upper notched ends of the rack-bars. The gage-plate D is next placed on top of and the saw forced down against the pressure of the 50 springs on the rock-shaft C^2 until the gage-bolts rest upon the clamping-bars, as shown in Fig. 3. Then tighten up on the hand-screws C^4 and secure the rack-bars in a stationary position before relaxing the pressure of the 55 gage-plate D on the saw. Then clamp the saw by rotating the cam-shaft. The saw is 60 now in position to be operated upon by the

hand set shown in Fig. 4 or hand-file-holding plates shown in Figs. 10, 11, 12, and 13.

The hand-plate D' is a tool for holding a 70 flat file in top-dressing the teeth, and is cut away on each side, so as to be more conveniently held in the hand. The under side is provided with a groove, d' , for the reception of the flat file d^2 , (see Fig. 12,) and near each 75 end, and on each side of this groove, with the inwardly-projecting ledges d^3 , on which the file rests being clamped in place by the screws d^4 . This hand tool or plate is also cut away on the under side to provide the edges d^5 , 80 which project down close to the edges of the clamping-bars and come to a gage bearing on the cap-plates as the operation of top-dressing the teeth progresses.

The hand-tool D^2 (see Figs. 11 and 13) is 85 designed to hold a three-cornered or angular file for side-dressing the teeth, as shown in Fig. 13. This tool consists of the side plate, d^6 , the top plate, d^7 , and the bottom or clamping plate, d^8 . The side plate is secured to the 90 top plate by screws d^9 . These plates are provided with turned-over edges forming lugs g , so as to be conveniently held in the hand.

The top plate, d^7 , is provided in the under side with the groove g^1 to receive one corner 95 of the file g^2 , (see Fig. 13,) and the bottom plate, d^8 , cut away or beveled on the upper front edge to correspond to the bearing-surface of the file and the angle at which it is set in order to bring the cutting-surface of 100 the file in contact with the saw-teeth at an oblique angle and in accordance with the shape of the same. The clamping-plate is 105 adjustably secured in place by means of the screws h . Both sides of the teeth may be 110 dressed or jointed with the same facility, as the tool D^2 may be used on either side of the saw. By this arrangement a saw may be conveniently held and dressed in the most expeditious manner possible and have every tooth 115 alike.

Having thus described my invention, what I claim, and desire to secure by Letters Patent, is—

1. The combination, with the supporting-frame, of a cap-plate rigidly mounted on one side of the frame, the vertical levers pivoted at their lower ends to said frame, a cam-shaft journaled in both said levers and frame, a second cap-plate rigidly mounted on the upper ends of said levers, and the clamping-bars mounted on the top of the respective cap-plates, whereby the movement of the cam-shaft throws the clamp into or out of a clamping position, substantially as and for the purpose set forth. 120

2. In a device of the character described, the combination, with the cap-plates and the clamping-bars, of the bolts a^1 , whereby said bars may be sprung or forced upward at the 125 ends, substantially as and for the purpose set forth.

3. In a device of the character described, the combination, with the supporting-frame,

of the rack-bars notched in the upper end and having a vertical movement, a rock-shaft journaled in the frame, and the pinions mounted on the rock-shaft and engaging with 5 the lower toothed end of said rack-bars, substantially as and for the purpose set forth.

4. The combination, with the rack-bars and the rock-shaft, of the pinions mounted on the latter, and the springs coiled on the respective ends of said shaft, whereby the rack-bars are automatically forced upward when the hand clamping-screws are relaxed, substantially as and for the purpose set forth.

5. The combination, with the frame having 15 openings b^2 in the upper part, of the rack-bars, and provided on their upper ends with guide-lugs which fit into said openings, the guide-brackets b^8 b^9 , and the hand-screws C^4 , substantially as and for the purpose set forth.

20 6. Jointly with the clamping device herein shown and described, the supplementary hand-gage tool consisting of the plate D, provided in each corner with an adjustable screw-bolt, d , substantially as and for the purpose 25 set forth.

7. Jointly with the clamping-device herein shown and described, the supplementary hand-tool consisting of the plate D' , grooved in the under side and provided with ledges d^3 , and the screws d^4 , for clamping the file in 30 place, substantially as and for the purpose set forth.

8. Jointly with the clamping device herein shown and described, the supplementary hand-tool D^3 , designed to hold a three-cornered file and consisting of the side plate, d^6 , the top plate, d^7 , grooved to receive one corner of the file, and the bottom or clamping plate, d^8 , and screws for adjustably-securing 35 said plate, whereby a three-cornered file may 40 be held to bring the cutting-face against the side of the saw-teeth at an oblique angle, as set forth.

MILO COVEL.
